UNITED STATES PATENT OFFICE.

HARRY BENWELL STOCKS, OF NORTHENDEN, ENGLAND.

SKEE-CYCLE OR SCOOTER.

1,237,969.

Specification of Letters Patent. Patented Aug. 21, 1917.

Application filed July 20, 1915. Serial No. 40,968.

To all whom it may concern:

Be it known that I, HARRY BENWELL STOCKS, a British subject, residing at Northenden, county of Chester, England, 5 have invented certain new and useful Improvements in Skee-Cycles or Scooters, of which the following is a specification.

This invention relates to a wheeled vehicle for juveniles of that type wherein a narrow frame or board is supported on two wheels, one at the front end of the frame or board, and the other at the rear end, upon which board or frame the rider stands upon one foot and maintains his balance while 15 propelling the device along by pushing the other foot on the ground and known under various names such as scooter, skee-cycle, foot-cycles and cycle-skates.

On gaining speed the rider balances himself with one foot on the foot board and is 20 carried forward by the momentum set up by the initial impulses this being a comparatively short distance.

This invention consists essentially in the 25 application to the frame or board of a foot support at one side of the longitudinal center thereof and a treadle on the opposite side of said longitudinal center and motion transmitting mechanism connected with the 30 rear wheel by which, after setting the machine in motion, the rider, while standing thereon, may propel it forward by a movement of the foot and at the same time maintain a proper balance.

35 The invention will be fully described with reference to the accompanying drawings.

Figure 1. is a side elevation of one form of the improved scooter or skee-cycle with a chain transmitting mechanism.

40 Fig. 2. is a plan of same with the steering handle removed.

Fig. 3. is a side elevation of the treadle and motion transmitting mechanism (enlarged).

45 Fig. 4. is a plan of same.

Fig. 5. is a side elevation of another form of the invention with a lever and toothed quadrant transmitting mechanism.

Fig. 6. is a plan of same.

50 Fig. 7. is a plan of similar arrangement with the treadle pivoted at or near its center.

Fig. 8. is an elevation of another form with two treadles and two quadrant levers actuated thereby.

55 Fig. 9. is a plan of Fig. 8.

The apparatus comprises a board or frame A having a foot rest A' at one side of its longitudinal center upon which one foot of the rider rests, said frame being supported 60 by a rear wheel B suitably journaled therein, and by a front wheel C journaled in a swiveling steering pillar D with a handle d, and a propelling mechanism actuated by a treadle E, pivoted upon and above the board 65 or frame A at the opposite side of the longitudinal center from the foot rest A' and connected with the rear wheel B to give motion thereto. The treads of the rear wheel B and the front wheel C are in a line 70 with the longitudinal center of the board or frame A.

In the construction shown in Figs. 1 to 4 a treadle E in the form of a cranked lever is pivoted to the side of the frame A to extend above the said frame and on the axle of the rear wheel B a sprocket wheel b is fitted with a free-wheel or one-way clutch b'. A chain e is attached to the rear end of the treadle lever E and passes over and engages the sprocket wheel b the other end being secured to a spring e' attached to the frame A. The rider sets the apparatus in motion standing with one foot on the foot-support A'. When a considerable speed has been attained further motion is transmitted to the rear wheel B by the other foot of the rider rocking the treadle E. The motion is applied to the wheel B in a forward direction on the upward movement of the chain 85 e the one-way clutch b' permitting the chain to return when drawn back by the spring e'. 90

In the construction shown in Figs. 5 and 6 the treadle E is pivoted by one end upon and above the frame A and at one side of the longitudinal center of same, the pivot being at or near the front of the frame. At its rear end the treadle lever is formed with a toothed quadrant e² gearing with a pinion b² on the hub of the rear wheel B. The pinion is fitted with a free-wheel or one-way clutch. Below the treadle E is a spring e' to normally raise the treadle to its highest position. In use when a considerable speed has been attained by the rider standing with one foot on the foot-support A' further motion is transmitted to the rear wheel B by the other foot of the rider rocking the treadle E. The motion is transmitted to the rear wheel B in a forward direction on the downward movement of the quadrant e² the one-way or free-wheel clutch of the pinion 100 105 110 115

*b*² permitting the quadrant to be raised by the spring *e*.

In the construction shown in Fig. 7 the treadle *E* is pivoted upon and above the frame *A* at one side of the longitudinal center of the latter and at a point about half way along its length so that it may be operated by both the toe and heel of the rider. The treadle lever is formed with a toothed quadrant *e*² gearing with a pinion *b*³ which may be either on the hub of the rear wheel *B* as in Fig. 5, or on an intermediate shaft *b*⁴ and provided with a sprocket wheel *b*⁵ from which the rear wheel is driven by a chain *b*⁶. A free wheel or one-way clutch is interposed either on the shaft *b*⁴ or on the hub of the rear wheel. In use when a considerable speed has been attained by the rider standing with one foot upon the foot-support *A'* further motion is transmitted to the rear wheel *B*, by the other foot of the rider rocking the treadle *E*. The motion is transmitted to the rear wheel *B* in a forward direction on the downward movement of the quadrant *e*² the one-way or free-wheel clutch permitting the quadrant *e*² to be raised either by the rocking of the treadle *E* or by a spring.

In the construction shown in Figs. 8 and 9 two treadles *E'* *E*² are pivoted at a point about half way of their length upon the frame *A*, one on one side, and the other on the opposite side of the longitudinal center of the frame, so that they may be rocked alternately or either may be rocked at will. Each treadle is formed with a toothed quadrant *e*² and each gears with a pinion *b*⁷ *b*⁸ which may be either affixed to the hub of the rear wheel as in Fig. 5 or loose on an intermediate shaft *b*⁴, each fitted with a free-wheel or one-way clutch affixed to the shaft *b*⁴, to which is also attached a sprocket wheel *b*⁵ from which the rear wheel is driven by a chain *b*⁶. One or both of the treadles may remain quiescent with the weight of the rider upon it, and may be used to stand upon in substitution for the foot-support previously described. In use when a considerable speed has been attained by the rider standing with one foot upon one of the treadles further motion is transmitted to the rear wheel *B* by the other foot of the rider rocking the other treadle. Or the motion may be transmitted to the rear wheel by the rider rocking both treadles simultaneously or alternately as he stands upon them. The quadrants operate to transmit motion as previously described.

What I claim as my invention and desire to protect by Letters Patent is:—

1. In a device of the class described, a

frame, a steering wheel and a rear wheel mounted, respectively, at the front and rear ends of the frame in alinement with the longitudinal center of said frame, a handle 65 for the steering wheel, a foot support at one side of the frame, a treadle at the opposite side of the frame and driving means between the treadle and the rear wheel.

2. In a device of the character described, 70 the combination with a frame, of a single wheel mounted in the rear portion of the frame and a single steering wheel mounted in the forward portion of the frame, said wheels being in line with each other, a handle for the steering wheel extending upwardly therefrom, a foot support carried by the frame and arranged on one side of the line between the treads of said wheels, a treadle also mounted on the frame and 75 arranged on the opposite side of the line between the treads of the wheels from the foot support, and means to transmit movement from the treadle to the rear wheel.

3. In a device of the class described, a 85 frame, a steering wheel and a driving wheel mounted, respectively, at the forward and rear ends of the frame, a handle for the steering wheel, said steering and driving wheels having their treads in line with the 90 longitudinal center of said frame, a foot support on said frame at one side of the longitudinal center of same, a treadle mounted on said frame at the other side of its longitudinal center, a sprocket wheel 95 loose on the axle of the driving wheel, a clutch between said sprocket wheel and said driving wheel adapted, when the sprocket wheel is moved in one direction, to impart movement to said driving wheel and, when the sprocket wheel is moved in the opposite direction, to permit it to overrun said driving wheel, and a chain connected to the treadle and passing over said sprocket wheel 100 to impart movement to said sprocket wheel 105 when said treadle is actuated.

4. In a two-wheeled coaster vehicle comprising a frame, a front wheel and a rear wheel in alinement, a support on the frame for one foot of the operator, a pedal for the 110 other foot movably mounted on the frame and connected to the rear wheel to propel the vehicle, and means for steering the vehicle.

In testimony whereof I have hereunto set 115 my hand in presence of two subscribing witnesses.

HARRY BENWELL STOCKS.
